UNITED STATES PATENT OFFICE.

RICHARD C. MORENUS, OF LAPORTE, INDIANA.

LIGHTING DEVICE FOR PLAYER PIANOS.

1,415,041.

Specification of Letters Patent.

Patented May 9, 1922.

Application filed January 29, 1921. Serial No. 440,871.

To all whom it may concern:

Be it known that I, RICHARD C. MORENUS, a citizen of the United States, residing at Laporte, in the county of Laporte and State 5 of Indiana, have invented certain new and useful Improvements in Lighting Devices for Player Pianos, of which the following is a specification.

My invention relates to player pianos and 10 consists in a lighting device for illuminating the roll located in the music well of the piano.

One object of my invention is to illuminate 15 the roll without casting a glare in the eyes of the operator or shedding a great deal of light throughout the room.

Another object of my invention is to provide means whereby the light may be automatically lit when the doors of the music 20 well are opened and will be automatically extinguished when these doors are closed.

In the accompanying drawings illustrating my invention—

Fig. 1 is a front elevation of the music well 25 and the sliding doors for same in closed position with my apparatus installed and with the piano case broken away to more clearly illustrate my invention.

Fig. 2 is a similar view with the doors in 30 open position.

Fig. 3 is a detail view on an enlarged scale 35 of the lamp, battery, switch and switch control element taken on the line 3—3 of Fig. 2 and

Fig. 4 is a detail top view of the same elements.

The doors 1 and 2 are slidably mounted on 40 tracks 3 and 4 and are adapted to open or close the music well opening 5 in the usual manner.

Secured near the top of the well is a block 45 6 which carries a battery 7 secured to the box by a strap 8 preferably of conducting material. A lamp socket 9 is mounted on the forward end of the block immediately over and slightly in advance of the right hand side of the music roll 10. A very small lamp 11 is screwed into socket 9. One pole 12 of the battery is connected direct to socket 50 9 and the other pole 13 is connected by means of strip 14, strap 8 and wire 15 to a flat spring 16 the forward end of which is adapted to move to and from the contact point of socket 9 in a vertical plane. It is obvious 55 that contact of spring 16 and the socket con-

tact point will close the circuit and light lamp 11.

To automatically depress spring 16 when the doors are opened and to release the spring when the doors are closed are the 60 functions of the lever mechanism illustrated in which a bar 17 is fixedly mounted on door 2 and a link 18 is pivotally mounted upon door 1 at 19. Lever 20 is pivoted intermediate its ends at 21 upon the piano box or 65 some other fixed point. The other end of link 18 is pivotally connected to one end of lever 20 and the other end of lever 20 is pivotally connected to bar 17 by a rod 22. Rod 22 carries a finger 23. 70

When the doors are opened, rod 22 is pulled to the right and its left hand end is first raised and then lowered by lever 20 so that it assumes the final position shown in Fig. 2. During the shifting of rod 22, finger 75 23 travels the path indicated by the dotted line in Fig. 2 and engages spring 16 from above, depressing the latter to contact with socket 9 and complete the lamp circuit.

When the doors are closed, the movements 80 of rod 22 and finger 23 are reversed and spring 16 is released from circuit closing position. This opening of the circuit takes place upon very slight closing movement of the doors and if the piano should be used in 85 the day time and the artificial light is not desired the doors may be moved toward each other far enough to raise finger 23 from spring 16 without reducing the well opening enough to interfere with the sight or replacement of the music roll 10. 90

If desired the lamp may be supplied with current from the ordinary house wiring equipped with a suitable switch and other necessary appliances. This and other modifications of my device may be made without departing from the spirit of my invention and I contemplate such changes in the application of my invention to player pianos. 95

I claim:

1. In a device of the class described, a music well, a lamp for lighting said well, a door for closing said well, a bar pivotally connected at one end with means on said door and pivotally connected at the other 105 end with a rocking support, and means operated by said bar for controlling said lamp.

2. In a device of the class described, a music well, a lamp to illuminate said well a door adapted to close said well, means for 110

mounting said door permitting greater opening movement than required for convenient access to said well, and means operated by the door in moving beyond the point necessary to give convenient access to the well for lighting said lamp.

3. In a piano, a music well, a lamp adapted to illuminate said music well, a pair of doors adapted to close and open said music well, means for constraining said doors to move in unison in closing and opening and permitting said doors to open wider than necessary to give convenient access to said well, and means operated by movement of the doors beyond the point necessary to give convenient access to the well for lighting said lamp.

4. In a piano, a music well, a lamp adapted to illuminate said well, a lamp switch,

doors for said well, a bar carried by one of said doors, a lever having a fixed pivot, a link connecting one end of said lever to the other of said doors, a rod connecting the other end of said lever to said bar, and a finger on said bar adapted to engage said switch.

5. In a piano, a music well, a lamp adapted to illuminate said well, a lamp switch, sliding doors for said well, a rod secured to one of said doors, a lever having a fixed fulcrum, adapted to be operated by the other of said doors, and adapted, when so operated, to raise and lower said rod, and an element on said rod adapted to close said switch when said rod is shifted by the opening of said doors.

RICHARD C. MORENUS.
